UNITED STATES PATENT OFFICE.

JESSE MARCROFT, OF PROVIDENCE, RHODE ISLAND.

AUTOMATIC TRAIN-STOPPING DEVICE.

1,192,086.

Specification of Letters Patent. Patented July 25, 1916.

Application filed May 5, 1913. Serial No. 765,638.

To all whom it may concern:

Be it known that I, JESSE MARCROFT, a citizen of the United States, residing at Providence, in the county of Providence and State of Rhode Island, have invented certain new and useful Improvements in Automatic Train-Stopping Devices, of which the following is a specification.

My invention relates to safety stopping-devices for railroad trains and consists of an improved mechanism for automatically shutting off the power and applying the brakes when a danger signal is set against the train.

The object of my improvement is to provide a device which will be absolutely positive in action, thoroughly reliable under all conditions and completely independent of the manual means of control for the engine, so as to be entirely beyond the control of the engineer.

The invention is fully described in the following specification, illustrated by the accompanying drawings, in which like letters of reference designate like parts.

In the drawings: Figure 1 illustrates a usual type of steam locomotive with my new stopping-device applied thereto; Fig. 2 is an enlarged, sectional view of the principal elements of the device; Fig. 3 is a rear-end view of the locomotive shown in relation to the rails and signal-mast to illustrate the electrical connection therebetween; Fig. 4 is an enlarged, detail view of the automatic electric-switch on the signal-mast; Fig. 5 is a view showing the electrical connections between the locomotive and the cars of the train; Fig. 6 is a diagram of one system of electrical wiring which may be employed to control the device.

I have preferred to herein illustrate and describe my invention as applied to a steam locomotive and arranged to be operated through steam pressure, but it is to be understood that the same mechanism might be operated by any fluid pressure, such as air, and therefore the device is adapted for use on electric locomotives or on other self-propelled engines.

Referring first to Fig. 1, A represents a well-known type of steam locomotive or engine having the usual longitudinal boiler B with the engineer's cab C at the rear end. On the top of the boiler B is the steam-dome

D from which the steam leads to the driving cylinders c through the main supply-pipe E, 55 see also Fig. 2. The steam is admitted to the pipe E through two opposite ports e, e, normally closed by a double throttle-valve F of the puppet type. The throttle-valve F is operated by a stem f connected to a bell-crank-lever f', which is controlled by a rod or link f''. The link f'' runs longitudinally of the boiler and is connected with the engineer's throttle-lever located in the cab of the engine, but not here shown. 65

The above designated elements are all common to the usual type of steam locomotive and my new mechanism is arranged in relation thereto as now described.

Between the throttle-valve F and the cylinders I place an auxiliary shut-off valve G in the pipe E adapted to entirely close said pipe to prevent the steam from reaching the cylinders to operate the engine notwithstanding the throttle may be open. The 75 valve G may be of any suitable form, but as here represented is of the "butterfly" type having a pivoted plate g arranged to swing across the opening of the pipe E when operated by the crank arm g'. 80

Tapped into the end of the main steam-pipe E is a relatively small pipe H which leads through a stuffing-box h in the side of the steam-dome D and is connected to a small cylinder or steam-chest J. The cylinder J serves as a valve-chamber and forms part of or is attached to a larger cylinder K, the two being connected at their lower ends by a pipe i or any suitable arrangement of steam duct. Adapted to slide in the valve chamber J is a balance-valve or double piston J' having two heads j, j arranged at a distance apart and normally positioned equidistant from the opening of the lead-pipe H. Two ports j', j'' in the side of the valve-chamber J are arranged to register with the piston heads j, j to be closed thereby when the piston J' is in its lowermost position. The ports j', j'' are connected by a duct j''' which renders them intercommunicating. The rod j' of the piston J' extends through a stuffing-box j'' and is connected at its end with a link or connecting-rod l. The opposite end of the link l is connected to one end of a lever or rocker-arm L pivoted at l' 105 on any suitable fixed support, not here

shown. Connected to the opposite end of the rocker-arm L is a link l^2 having its lower end attached to a hinged arm M which serves as an armature for the electro-magnet M'. A suitable coiled spring σ attached to the arm L serves to normally maintain the armature M in a raised position away from the ends of the magnet M'. The magnet M' as here shown is of a well known type having two coils m , m and the usual axial cores m' , m' . In place of this arrangement however, the common form of solenoids might be employed with their armatures attached to the link l^2 and arranged to slide in the coils. One lead from the magnet M' is connected to a battery N by the wire n and the opposite lead grounded in the frame of the locomotive at n' .

The cylinder K is designed to serve as the main source of power for actuating the mechanism which shuts off the power of the engine and operates the brakes of the train. Arranged to slide in the cylinder K is a piston K' having its rod k extending through a stuffing-box k' and pivotally attached to the connecting-rod p . The rod p has its opposite end connected to one arm of a bell-crank-lever P which is pivoted at p' to any suitable bracket or standard, not here shown, attached to the frame of the engine. The opposite arm of the lever P is connected to a link or rod P' which extends to the arm g' to adapt it to operate the valve G in the main steam-pipe E. A spring p^2 serves to normally maintain the lever P in the position illustrated in Fig. 2 with the piston K' adjacent the bottom of the cylinder K.

The air-brakes of the train are usually controlled through the relief of air-pressure which normally acts to hold the brake mechanism inoperative. For this purpose the engine carries an air tank I sometimes arranged at the side of the cab C as illustrated in Fig. 3, and connected with a pipeline leading through the cab and thence to the several coaches of the train. The engineer's brake-operating valve is located on this line, within convenient reach in the cab, and the pipe leading therefrom is shown in Fig. 1 and designated q . The pipe q connects with the brake-operating mechanism of the coaches through a main line q' having couplings q^2 , and for convenience of illustration I have shown my stopping-device arranged to operate a relief-valve R located at the end of a pipe r leading from the pipe q' . Referring to the enlarged view of the mechanism, Fig. 2, the valve R may be of any suitable type and as here shown is operated by a lever r' connected by a rod or link r^2 , leading to the bell-crank-lever P.

For the sake of clearness I have shown the elements of the device above described as exposed to view on the outside of the locomotive. It is to be understood, however,

that in practice certain parts of the device can be inclosed within the shell of the boiler and the main operating-mechanism covered by a casing attached to a suitable shelf or bracket secured on the side of the engine.

70

Referring to Figs. 1 and 3, one pole of the battery N is connected by a wire s to a contact-shoe S located at any convenient point on the engine frame.

75

For convenience of illustration I have shown the shoe S at the rear of the driving wheels, but the preferable arrangement would be to place it either under the pilot or between the wheels.

80

In either of these positions it will then be out of the way and beyond reach from the outside so as to prevent disconnection of the wiring or interference with its operation. The shoe S may be of any suitable form ar-

85

ranged to be pressed against a contact-rail T running parallel with the main rails T', T^2 . As here illustrated the shoe S is pressed into contact with the rail T by a coiled spring s' on the rod s^2 and these parts are insulated from the iron-work of the engine by suitable means, such as the wooden block s^3 .

90

Any other arrangement of contact-shoe and rail could be used in place of that here shown; for instance the usual third-rail system of electric roads might be employed. The contact-rails T are placed alongside the main rails, either inside or outside thereof, at points adjacent the signal-masts of the block-signal system now generally used on railroads. In Fig. 3 I have shown a usual form of signal-mast U having a pivoted

95

semaphore-arm U' at the top arranged to be actuated through the vertical rod u . The rod u is operated through the usual mechanism, not here shown, which is controlled from the signal tower or despatching station by either mechanical or electrical means. Mounted on or formed as a part of the mast U, I provide a switch-box v in which is incased the circuit-closing switch V for the electrical controlling-means for the stopping-device.

100

The switch V may be of any suitable form, but as here shown is of the "knife" type having a blade v' pivoted at one end on a binding-post v^2 . The outer end of the blade v' is connected to the rod u , preferably through a pin-and-slot arrangement shown at v^3 . A second binding-post v^4 is provided with the usual spring-contacts adapted to impinge upon the blade v' . From the binding-post v^2 a wire t leads to one of the main rails T', being electrically connected therewith; and a second wire t' leads from the post v^4 and is electrically connected with the contact-rail T.

105

The above described mechanism with its electrical connections is sufficient in itself to accomplish the object of the present invention, that is, the automatic stopping of the train through the operation of the signal system, as hereinafter fully explained. To

110

125

130

135

make the device more dependable and efficient, however, and to provide for its manual control from the several cars or coaches of the train I provide the additional electrical connections shown in Fig. 5 and now described: Connected with the wire s leading from the battery N is a wire w or other conductor arranged to extend the length of the train. That is to say, each car or coach will be wired on a lead w from the battery N to connect with every other car. This wiring can be carried in suitable conduits arranged to be coupled with the air-pipe couplings at the ends of the cars. On one of the trucks of each car I provide contact shoes S' , S^2 , etc., see Fig. 6, having electrical connections w' , w^2 , etc., leading from the wire w . These shoes may be similar in form to the shoe S carried by the locomotive and, like the latter, are insulated from all other parts of the cars. Their operation and purpose are also the same as that of the shoe S , that is, to close the electrical circuit to energize the magnet M' , as more fully explained hereinafter.

Through this arrangement I provide a plurality of contacts which insure a more reliable control of the device and guard against failure of operation should the contact shoe on the engine become broken or deranged.

Another advantage in this extended system is that the contact-rails along the tracks can be made shorter, since a relatively long period of time will elapse during the passage of the whole train over a given length of rail, and hence there can be no danger of the train coasting beyond the signal and then being started again. Still another benefit arising from the continuous circuit throughout the train is that it allows for placing emergency-switches in the coaches, which take the place of the usual conductor's valve for the air-brakes, and can be operated in case of accident or should other occasion require. Referring again to Figs. 5 and 6, I propose to install in each coach a hand-switch W arranged as follows: Any suitable manually-operable type of switch can be employed for this purpose and as here shown one of its contact-points w^3 is connected by a wire w^4 leading to the wire w which connects with the contact shoe S through the wire w' , while the other contact point w^5 has a wire w^6 grounded in the metal-frame of the truck x of the coach X . A hand-lever w^7 of the knife-blade type, or of any other suitable form, is arranged to be thrown to connect the two contacts. The switch W is preferably inclosed in a suitable case W' which may be sealed with a glass-door similar to those used for fire-alarm boxes. In this way the switch would be protected from malicious or ignorant tampering, while at the same time being easy of access for those in authority.

The operation of my complete device is as follows: The contact-rails T , as before explained, are placed at points adjacent the signal-masts U , beyond the latter and within the "blocks" which the trains approach when a "distant" signal is employed, but in advance of the "blocks" when only a "home" signal is used. They may also be used in connection with switches or crossovers, in which case they are placed in advance of the latter to slow down or completely stop the train before it gets to the switch or crossover. With the arrangement of block-signal system generally employed on railroads it is usual to control the blocks in pairs as follows: If one block is closed the next previous one will have its signal set at "caution" and this "distant" signal, as it is called, warns the engineer to slow down his train so that he can come to a full stop before entering the next block should the "home" signal be set at danger. In some cases, however, only two positions of the semaphore are provided for, one indicating that the block is clear and the other that it is closed. My device can be applied to either system, but for the sake of simplicity I prefer to illustrate and describe its operation in connection with the one last described.

Referring to Fig. 3, the semaphore arm U' is here shown in its raised position at "danger", indicating that the block is closed. When the arm U' is carried up into this position through the operation of the rod u the movement of the latter actuates the switch-blade v' to carry it between the spring contacts on the binding-post v^4 , as shown by full lines in Fig. 4. The closing of the switch V acts to connect the rails T and T' through the wires t and t' and in this way the contact-rail T is electrically connected with the rail T' . Now as the train approaches the block if the engineer fails to observe the signal and does not stop the shoe S will come into contact with the rail T and complete the electrical circuit. The closing of the circuit operates the stopping-device in the following manner: The current from the battery N passes from one pole thereof through the wire n to the magnet M' and thence through the wire n' which is grounded in the frame of the locomotive to bring all of the metal parts thereof in circuit. Now, since the wheels of the locomotive constitute a part of the circuit, the current will pass therethrough to the rail T' and thence through the wire t , switch V and wire t' to the contact-rail T . From the rail T the circuit is completed through the shoe S and wire s which leads therefrom to the other pole of the battery N . From the above it will be seen that the operation of the switch V as before described will close the circuit leading from the battery and including the magnet M' and hence when this takes place the magnet-coils will

be energized to attract the armature M. As the armature M is moved downward it acts through the link l^2 to rock the arm L and the movement of the latter causes the link l to raise the balance-valve J', see Fig. 2.

It will be understood, of course, that when the throttle F is open the steam from the dome D will be admitted to the pipe E and thence to the pipe H to maintain pressure in the valve-chamber or cylinder J. On account of the double piston-head construction of the valve J' this pressure will be exerted equally against both heads j , j , and hence the valve will normally remain "balanced" in the position illustrated in Fig. 2, without any tendency to move one way or the other. When, however, the valve J' is raised by the action of the magnet M' the heads j , j will slide past the ports j^2 , j^2 to open the latter. The opening of the ports j^2 , j^2 admits steam through the upper one and allows it to pass through the duct j^3 and back into the cylinder J through the lower port so that pressure is exerted against the lower end of the piston J' to assist and accelerate the movement of the latter. At the same time, the movement of the piston or valve J' admits the steam to the pipe i which leads to the cylinder K and consequently pressure is exerted against the lower end of the piston K'. This pressure forces the piston K' upward in the cylinder K and through the connecting-rod p acts to rock the bell-crank-lever P against the action of its spring p^2 . The rocking motion of the lever P actuates the rod P' to turn the crank-arm g' and close the auxiliary shut-off valve G. In this way the steam is entirely shut off from the driving-cylinders of the engine and hence the latter becomes inoperative or "dead" and must stop.

To expedite the stopping of the train and prevent its coasting on a down-grade I have adapted my mechanism to effect the operation of the air-brake simultaneously with the shutting off of the power of the locomotive. As here shown, this part of the device consists simply of the link or rod r^2 connecting the lever P with the relief-valve R and acting to open the latter when the steam-valve G is closed by the automatic operation of the piston K'. The relief of air-pressure in the pipe r, which leads from the main pipe line of the brake-system, causes the operation of the brakes in the well known manner throughout the whole train. This brake-controlling mechanism is not absolutely necessary to the successful operation of my device and could be eliminated if desired. For instance, if the device were used only for slowing up trains at switches, crossovers, etc., it might not be required to apply the air-brakes and therefore only the steam-valve operating connections would be needed. At the same time, the

device would be more efficient for all purposes if adopted in its entirety and therefore the complete arrangement is preferable. For instance, my new device is much more practical and effective as an emergency-stop controlled from the coaches than the usual means of control through the conductor's valve. With this latter device the power cannot be controlled from the coaches, but only the air-brakes. Therefore, if emergency requires the stopping of the train by the conductor and his only means is the air-valve, then the brakes will be set while the power remains on and consequently they will not have their maximum efficiency. Besides this, when the brakes are set against the power of the engine the shock and strain on the running gear are enormous and liable to cause derailment and great damage. With my new device it is only necessary for the conductor or any other authorized person to throw one of the switches W located in the coaches and the electrical circuit will be completed to actuate the stopping-mechanism as previously described. In this way the power is cut off from the engine and the brakes applied simultaneously so that the train will come to a stop in a very short time. This adaptation of the device is especially valuable as providing against the locomotive running away or getting beyond control, due to incapacity of the engineer through accident, sickness or death.

After the train has been stopped through the operation of the signal-switch it is impossible to start it again until the signal is returned to its "clear" position. The engineer may manipulate his throttle as much as he pleases, but as long as the armature M remains attracted by the magnet M' steam will be admitted to the cylinder K to maintain the piston K' raised and the auxiliary shut-off valve G closed. Another advantageous feature of my device is that the engine will not start of itself even if the throttle is left open when the signal is returned to clear and the electric circuit becomes interrupted or broken. When this takes place the magnet M' will be deenergized, but its armature cannot be raised because the pressure of the steam admitted by the open throttle to the pipe H retains the valve J' in its raised position. Under these conditions the ports j^2 , j^2 will remain open to admit steam to the cylinder K and this pressure keeps the piston K' raised to hold the shut-off valve G closed. To start the engine the engineer must first close his throttle. This relieves the pressure in the chamber J and cylinder K and the natural condensation of the steam or the slight leakage which inevitably takes place where there are valves and joints, will allow the piston K' to be returned to its normal position, as illustrated in Fig. 2, under action of the

spring p^2 on the lever P. Now, when the magnet M' is deenergized the armature M will be released to allow the return of the valve J' under action of the spring o, and hence when the throttle is opened again the ports j^2 , j^2 will have been closed. This renders the piston K' inoperative so that the valve G remains open and the engine can therefore be started again. To effect a quicker release of the pressure in the valve-chamber J and cylinder K the engineer can open the air-cocks on the main cylinders through the operation of the lever usually provided. If desired a small relief-valve could be applied to the cylinder K and this might be arranged to be operated automatically.

One important advantage of my new device is that it can be applied to any type of steam locomotive now in use without material change in the mechanism of the latter. All that is required to put the device into practice is to mount its main operating parts on the engine in any convenient location and to connect it with the main steam-supply pipe for the cylinders. This connection simply necessitates an auxiliary shut-off valve in the steam-pipe E and a small pressure supplying pipe H leading therefrom.

As before stated, the same arrangement of mechanism can also be adapted to control the operation of electric locomotives by slightly modifying its connections. For instance, the pressure necessary for operating the piston K' could be supplied by air taken from the main air-tank used for supplying the brake-mechanism as now generally arranged. The pipe H would then be connected to lead from the air-tank with a valve arranged to control the pressure. This valve would be operated automatically from the controller-devices for the motors so that when the locomotive was under power air would be admitted to the valve-chamber J.

Upon the closing of the circuit and energizing of the magnet M' the valve J' would be moved to admit air to the cylinder K. This air-pressure would then actuate the piston K' to throw a cut-out switch and shut off the power from the motors. This cut-out switch would of course be independent of the manually-operated controller-devices of the locomotive, just as the shut-off valve G is independent of the main throttle F of the engine hereinbefore described, and all of such connections would be so simple that illustration is hardly necessary. It will also be obvious that my improved device might be operated by air-pressure even when applied to a steam locomotive. That is to say, instead of leading the pipe H from the steam-pipe E, as first described, it might be led from the air-tank and with this arrangement there would be a valve in said pipe adapted to be opened automatically.

cally when the throttle is opened. It will be understood that any of these modifications might be made within the scope of the present invention.

While my device as above described is designed to be controlled by electrical means it might easily be adapted for operation through a mechanical trip-contact. Such an arrangement, however, would not be reliable, as it would be more liable to be rendered inoperative from outside influence, particularly in stormy weather, and could be tampered with more easily.

It will also be obvious that my new stopping-device might be operated independently of the signal-mechanism. That is to say, the circuits could be closed by switches located at the signal-towers or despatching stations without dependence on the movement of the semaphore arms.

Various modifications might be made in the form and arrangement of my new device without departing from the spirit or scope of the invention.

Therefore, without limiting myself to the exact construction shown and described, what I claim is:—

1. In an automatic stopping-device for railroad trains, the combination with a locomotive having manually-operated power-controlling means, of means outside the control of the operator for shutting off the power without operating the manual means, a fluid-controlled device for operating said shut-off means, means controlled by the power-controlling means to maintain pressure in said fluid-device during the operation of the locomotive, and automatically-actuated means controlled by danger conditions to release the pressure to operate the shut-off means.

2. In an automatic stopping-device for railroad trains, the combination with a locomotive having manually-operated power-controlling means, of means outside the control of the operator for shutting off the power without operating said first-named means, a fluid-controlled device for operating said shut-off means, means operated by the power-controlling means to maintain pressure in said fluid-device when the power is on, and electrically-controlled means to release the pressure to operate the shut-off means.

3. In an automatic stopping-device for railroad trains, the combination with a locomotive having manually-operated power-controlling means, of means outside the control of the operator for shutting off the power without operating said first-named means, a fluid-controlled device for operating said shut-off means, means connected with the power-controlling means to maintain pressure in said fluid-device during the operation of the locomotive, a signal-sys-

tem, and means operated through said signal-system to release the pressure to operate the shut-off means.

4. In an automatic stopping-device for railroad trains, the combination with a locomotive having manually-operated power-controlling means and power-actuated brakes, of means outside the control of the operator for shutting off the power and applying the brakes without operating the manual means, a fluid-controlled device for operating said shut-off means and brake-applying devices, means operated by the power-controlling means to maintain pressure in said fluid-device during the operation of the locomotive, and automatically-operated devices controlled by danger conditions to release the pressure to simultaneously shut off the power and apply the brakes.

5. In an automatic train-stopping device, the combination with a locomotive having manually-operated throttle-valve for controlling the steam supplied to the cylinders, of an auxiliary shut-off valve adapted to be operated without operating the throttle-valve, a fluid-pressure device for operating said shut-off valve, means controlled by the operation of the throttle-valve to maintain pressure in the fluid-device during the operation of the locomotive, and automatically-operated means controlled by danger conditions to release the pressure to cause the closing of the shut-off valve to effect the stopping of the train.

6. In an automatic train-stopping device, the combination with a locomotive having a manually-operated throttle-valve, of an auxiliary shut-off valve adapted to shut off the steam while the throttle-valve is open, a fluid-pressure device for operating the shut-off valve, means controlled by the operation of the throttle-valve to maintain pressure in said fluid-device when the throttle is open, and automatic devices controlled by danger conditions for releasing said pressure to operate the shut-off valve to effect the stopping of the train.

7. In an automatic train-stopping device, the combination with a locomotive having a manually-operated throttle-valve for controlling the power thereof, an independent shut-off valve between the throttle-valve and the cylinders, a steam-pressure operated device for closing said shut-off valve, means to admit steam to said device through the throttle-valve, and automatically-operated devices controlled by danger conditions to release the steam-pressure to close the shut-off valve to stop the train.

8. In an automatic train-stopping device, the combination with a locomotive having a manually-operated throttle-valve for controlling the power thereof, a separate shut-off valve between the throttle-valve and the

cylinders, a fluid-pressure device for closing said shut-off valve, a valve-chamber in said device, means controlled by the operation of the throttle-valve to maintain pressure in the valve-chamber, a valve to release the pressure, a magnet to operate the valve, and means outside the train for causing the magnet to be energized to move the valve.

9. In an automatic train-stopping device, the combination with a locomotive having manually-operated means for controlling the power thereof, of means for shutting off the power without operating the manual means, a fluid-pressure device for operating said shut-off means, a valve-chamber in said device, means operated by the power-controlling means to maintain pressure in said valve-chamber while the power is on, a valve normally maintained balanced against said pressure, and automatically-operated means controlled by danger conditions to move said valve to overcome its balance and release the pressure to operate the shut-off means.

10. The combination with a locomotive having manually-operated power-controlling means, of auxiliary means for shutting off the power without operating the manual means, a fluid-pressure cylinder, a piston in said cylinder connected to operate the shut-off means, a valve-chamber communicating with said cylinder, a double-headed piston valve in said chamber, means to maintain pressure in the valve-chamber during the operation of the locomotive to hold the valve normally balanced, and automatically-actuated devices controlled by danger conditions to operate the valve to overcome the balance to admit pressure to the cylinder to operate the shut-off means.

11. The combination with a locomotive having manually-operated power-controlling means, of auxiliary means for shutting off the power without operating the manual means, a fluid-pressure cylinder, a piston in said cylinder connected to operate the shut-off means, a valve-chamber communicating with said cylinder, a double-headed valve in said chamber, means to maintain pressure in said valve-chamber, two intercommunicating ports in the chamber normally closed by said valve, and automatically-operated means controlled by danger conditions to move the valve to open the ports to admit pressure through one of them to pass through the other and enter the cylinder to operate the piston therein.

12. The combination with a locomotive having manually-operated power-controlling means, auxiliary means for shutting off the power without operating the manual means, a fluid-pressure cylinder, a piston in said cylinder connected to operate the shut-off means, a valve-chamber communicating with said cylinder, a double-headed piston

valve in said chamber, intercommunicating ports in the chamber normally closed by said valve, means to admit pressure against both heads of the valve to maintain the latter balanced, and means to move the valve to open the ports to admit pressure against the end of the valve to accelerate the movement of the latter and release the pressure to operate the shut-off-operating piston.

13. In a train-stopping device, the combination with a locomotive, of means to shut off the power thereof, a piston for operating said means, a cylinder in which the piston slides, a valve-chamber communicating with said cylinder, two intercommunicating ports in said valve-chamber, a double-headed piston valve in said chamber arranged to normally close both ports, means to admit pressure to the valve-chamber to maintain the valve balanced, and means to move the valve to open the ports to admit pressure through one of them and allow it to pass through the other to enter the cylinder and operate the piston therein.

14. In a train-stopping device, the combination with a locomotive, of means to shut off the power thereof, a piston connected to operate said means, a cylinder in which the piston slides, a valve-chamber communicating with said cylinder, means to maintain

pressure in said valve-chamber, two intercommunicating ports in said valve-chamber, a valve adapted to normally close both of said ports, an electro-magnet, an armature connected to the valve, and means to energize the magnet to attract the armature and operate the valve to admit pressure to the cylinder for operating the piston therein.

15. In a train-stopping device, the combination with the main steam-pipe of the locomotive, of a shut-off valve therein, a lever for operating said valve, a piston for actuating the lever, a cylinder in which the piston slides, a valve-chamber communicating with said cylinder, a pipe leading from the main steam-pipe to the valve-chamber, two intercommunicating ports in the valve-chamber, a double-headed piston valve adapted to be normally balanced by the steam-pressure to close both ports, and means to move the valve to admit steam through one of the ports and out through the other and thence into the cylinder to operate the piston therein.

In testimony whereof I affix my signature in presence of two witnesses.
